UNITED STATES PATENT OFFICE

110,384

DESIGN FOR A RAIL CAR OR SIMILAR ARTICLE

Dan H. Bell, Pittsburgh, Pa., assignor to Transit Research Corporation, New York, N. Y., a corporation of New York

Application January 8, 1937, Serial No. 66,952

Term of patent 3½ years

To all whom it may concern:

Be it known that I, Dan H. Bell, a citizen of the United States, residing at Pittsburgh, in the county of Allegheny and State of Pennsylvania, have invented a new, original, and ornamental Design for a Rail Car or Similar Article, of which the following is a specification, reference being had to the accompanying drawing, forming part thereof.

Figure 1 is a side elevation of a rail car or similar article showing my new design.

Figure 2 is a top plan view of the car, Fig. 3 is a rear elevational view, a portion of the trolley pole being broken away for convenience of illustration; and Fig. 4 is a front elevational view with the trolley pole broken away as in Fig. 3.

I claim:

The ornamental design for a rail car or similar article, as shown and described.

DAN H. BELL.
